his Attorney.

UNITED STATES PATENT OFFICE

CARL OTTO, OF ESSEN-BREDENEY, GERMANY

VACUUM CLEANING APPARATUS

Application filed February 8, 1930, Serial No. 427,018, and in Germany March 23, 1929.

My invention relates to improvements in vacuum cleaning apparatus, and more particularly in apparatus of the type comprising an automatically operated beater. The 5 object of the improvements is to provide an apparatus of this class which is effective in operation, and with this object in view my invention consists in mounting the beater on a member having a circular path. 10 The said member may have a circular reciprocating movement. But I prefer to rotate the same, for example by means of an electromotor.

Another object of the improvements is 15 to provide an apparatus having a high sucking action, and with this object in view the blades of the exhauster are mounted on the said rotary member and disposed so that they produce the vacuum for taking 20 the dust from the surface to be cleaned, or that they assist the action of the main exhauster or vacuum pump.

For the purpose of explaining the invention an example embodying the same has 25 been shown in the accompanying drawing in which the same reference characters have been used in all the views to indicate corresponding parts. In said drawing,

Fig. 1 is a sectional elevation showing 30 the mouthpiece of the vacuum cleaning apparatus, and

Fig. 2 is a sectional elevation taken on the line 2—2 of Fig. 1.

In the example shown in the figures the 35 casing *a* providing the mouthpiece of the vacuum apparatus has the axle *b* of the armature *c* of an electromagnet fixed thereto, and on the said axle a cylindrical casing *d* providing a short-circuit rotor is rotatably mounted. The axle *b* is provided with a longitudinal bore for the leads of the 40 armature. The outer wall of the casing *d* carries longitudinal ribs or cleats *e* and brushes *f* for beating and brushing the 45 surface to be cleaned. The casing *d* is provided with elongated hubs *o* having propellers *g* and *h* secured thereto, the said propellers forming parts of a suction device. Preferably the said propellers are 50 separated from the inner part of the mouth-

piece containing the beater *e*, by partitions *p* of hood *i* formed with openings *k* and *m* disposed concentrically of the hubs *o*.

In the operation of the apparatus three-phase current is supplied to the armature *c*, so that the rotor *d* is rapidly rotated, the brushes *f* and ribs or cleats *e* engaging the surface to be cleaned and having a beating and rubbing action thereon. In apparatus in which the mouthpiece *a* is connected by the tubular extension *n* to an exhauster or air pump the fans or propellers *g*, *h* assist the action of the said pump. By the increased suction action of the combined pump and fans the carpet or the like 65 is lifted from the floor, so that the beating action is improved.

The apparatus may also be used merely for removing dust from furniture, curtains or the like, in which case the beating apparatus *e* remains inoperative.

The construction of the beating apparatus and its operating mechanism shown in the figures is particularly simple, and it requires little room. But I wish it to be 75 understood that I do not limit myself to the construction shown in the figures in which the beating members are mounted on the rotor of the electromotor, but include within the scope of my invention all modifications as to form and arrangement of elements as defined by the herein appended claims.

The cleaning action is particularly effective, because the beating members impart 85 blows to the carpet or the like which are more or less in the direction of the surface of the carpet, and the said beaters have the function to loosen the dust from the carpet, so that it is more readily removed by the 90 vacuum device.

The operation of the apparatus and the possibility of moving the same across the surface to be cleaned is not in any way interfered with by the beater, so that the apparatus may be used for cleaning any surfaces, such as floors, curtains and furniture.

I claim:

1. In vacuum cleaning apparatus, a casing having a mouthpiece, a hood in the 100

mouthpiece, provided with openings in its side walls, in communication with suction channels formed between the casing and the hood, an electromotor in the hood having a stationary armature fixed to the walls of the casing, a rotor surrounding the armature provided with hubs extending into the suction channels, means on the rotor for loosening dust from the surface to be cleaned, and a propeller carried by each of the hubs of the rotor for producing a suction action whereby dust is led from the hood into said mouthpiece.

2. In a vacuum cleaning apparatus, a mouthpiece having an open bottom, a hood within said mouthpiece and spaced therefrom and open at its bottom, an electromotor within said hood having a stationary inner part secured to the wall of the mouthpiece and a rotary outer part having hubs extended through said hood into the space included between the same and the mouthpiece, agitating means extending from said outer rotary part into the openings of the hood for cleaning the surface below said openings and suction producing devices secured to said hubs within the said space of the mouthpiece, said hood being provided with openings disposed concentrically of the hubs.

3. In a vacuum cleaning apparatus, a mouthpiece, a hood within the mouthpiece with openings in the side walls, said hood and mouthpiece being spaced apart to form suction channels in communication with said openings, a rotatable member within said hood and mouthpiece, agitating means on said rotatable member for dusting and beating the surface to be cleaned, the periphery of said member lying substantially flush with the bottom of said mouthpiece, electric driving means within said rotatable member for imparting rotary movement thereto, whereby the surface to be agitated is directly below the open portion of the mouthpiece and exposed to the direct agitating action of the rotatable member, and means on the ends of the rotatable member and in the suction channels for setting up a suction action in the hood and channels to draw up the surface to be agitated, against the opening of the hood.

4. A vacuum cleaning apparatus, having a mouthpiece with a wide opening at its base portion, an electromotor within the mouthpiece having its rotor circumferentially provided with agitating means thereon for loosening and brushing dust from surfaces below the opening of said mouthpiece, and its armature permanently fixed to the walls of the mouthpiece, and suction means on the rotor whereby the dust raised by the agitating action of the rotor on the surface to be cleaned is drawn into the mouthpiece.

5. A vacuum cleaning apparatus, comprising a casing with an opening at its base and with dust conducting channels therein, an electromotor within the casing and in the channels having an outer rotatable member with agitating means extending out of the opening of the base for cleaning surfaces below said opening, and sucking means on the rotatable member in the channels for drawing up the dust raised by the action of the rotatable member through said opening into the dust conducting channels.

6. A vacuum cleaning apparatus comprising a mouthpiece, a hood having apertures within the mouthpiece dividing the mouthpiece into two compartments, an electromotor with its shaft fixed to the mouthpiece and within the hood compartment, an external rotary peripheral member within the hood compartment and rotatable on said shaft, said member having on its circumference means for loosening dirt on the surface to be cleaned, and propellers on the other side of the hood and within the mouthpiece compartment and on the rotary member for sucking in the dust from the surface to be cleaned, whereby the sucking action of the propellers will draw the dust into the hood compartment through the apertures and into the upper part of the mouthpiece compartment.

7. In a vacuum cleaning apparatus, having an oblong shaped casing with an opening in its base portion, the improvement comprising a hood enclosed by said casing having openings at opposite sides thereof and a cleaning chamber underneath the same, said hood and casing being spaced apart to form suction channels in communication with said openings and the cleaning chamber, an electromotor extending through the casing having a rotor portion provided with agitating means in the hood, and suction means on the rotor, mounted in the channels whereby upon rotation of said rotor the dust is drawn into the suction channels.

In testimony whereof I hereunto affix my signature.
